UNITED STATES PATENT OFFICE

102,709

DESIGN FOR A BROOCH OR SIMILAR ARTICLE

Charles Adler, New York, N. Y.

Application November 27, 1936, Serial No. 66,153

Term of patent 3½ years

To all whom it may concern:

Be it known that I, Charles Adler, a citizen of the United States of America, residing in Manhattan, county of New York, and State of New York, have invented a new, original, and ornamental Design for a Brooch or Similar Article, of which the following is a specification, reference being had to the accompanying drawing, forming part thereof, wherein,

The particular initials shown are merely illustrative.

I claim:

The ornamental design for a brooch or similar article, substantially as shown and described.

CHARLES ADLER.
